Primary Examiner—A. Hugo Word
Assistant Examiner—Cynthia E. Ramirez
Attorney, Agent, or Firm—John E. Reilly[57] **CLAIM**

The ornamental design for a multi-purpose hand-held rotary drive cleaning tool, as shown and described.

DESCRIPTION

FIG. 1 is a perspective view showing our new design;
FIG. 2 is a front view in elevation thereof;
FIG. 3 is a rear view in elevation thereof;
FIG. 4 is a left side view in elevation thereof;
FIG. 5 is a right side view in elevation thereof;
FIG. 6 is a perspective view when viewed from the upper end portion of our new design; and,
FIG. 7 is a bottom view.

The broken line showing of the attachment of FIG. 1 is for illustrative purposes only and forms no part of the claimed design.
